DESIGN FOR A COMBINED VESTEE AND HOOD

Harry Kaufman, New York, N. Y.

Application June 4, 1945, Serial No. 119,903

Term of patent 7 years

(Cl. D3—25)

To all whom it may concern:

Be it known that I, Harry Kaufman, a citizen of the United States of America, residing in New York city, county of Bronx, and State of New York, have invented a new, original, and ornamental Design for a Combined Vestee and Hood, of which the following is a specification, reference being had to the accompanying drawing, forming part thereof, wherein,

Figure 4 is a similar view showing the hood thereof in an unbuttoned position and folded back.

I claim:

The ornamental design for a combined vestee and hood, substantially as shown.

HARRY KAUFMAN.
